UNITED STATES PATENT OFFICE.

ARTHUR C. JACKSON AND WALDEMAR KROLL, OF PHILADELPHIA, PENNSYLVANIA,
ASSIGNORS, BY MESNE ASSIGNMENTS, TO THE YALE & TOWNE MANUFACTURING
COMPANY, OF STAMFORD, CONNECTICUT, A CORPORATION OF CONNECTICUT.

PADLOCK.

Application filed May 3, 1923 Serial No. 636,399.

The object of our invention is to design a padlock so that it can be secured to a grooved pin, or bolt, made in one or two parts so that, while the lock will turn freely 5 on the pin, it cannot be removed therefrom without a key.

The present invention is especially adapted for securing spare wheels to the carrier of an automobile. These spare 10 wheels are usually secured to the carrier by two or more pins. One of the pins is generally provided with a transverse hole to receive the shackle of an ordinary padlock.

It will be understood that the invention 15 can be used for other purposes without departing from the essential features of the invention.

In the accompanying drawings:

Fig. 1 is a face view of the lock, showing 20 it mounted on a grooved pin;

Fig. 2 is a sectional view on the line 2—2, Fig. 1;

Fig. 3 is a face view, partly in section, 25 showing the lock engaging the grooved portion of the pin;

Fig. 4 is a detached perspective view of the lock, showing the shackle raised;

Fig. 5 is a perspective view of one form 30 of pin to which our improved lock can be applied;

Figs. 6 and 7 are views illustrating a modification of the invention, in which the pin has a flat side;

Figs. 8 and 9 are views illustrating 35 another modification, in which the side plates of the casing are shaped to enter a groove on each side of the groove in which the shackle is located;

Fig. 10 is a side view, partly in section, 40 showing a rib at one side of the shackle;

Fig. 11 is a face view of a lock having a 45 sliding shackle arranged to engage a pin;

Fig. 12 is a view showing a modification of the pin;

Fig. 13 is a view showing the invention applied to a door;

Figs. 14 and 15 are views illustrating the invention applied to a two-part pin; and

Fig. 16 is a view illustrating the pin made 50 of pressed sheet metal.

Referring to Figs. 1 to 5 of the drawings, 1 is a pin having a reduced portion in the form of an annular groove 2. In the present instance, this pin is secured to the spare

wheel frame of an automobile and passes 55 through the hub 3 of the spare wheel. 4 is the lock casing and 5 is the shackle pivoted at 6 to the casing. The casing has a body portion 8, a cap plate 9, and a back plate 10, which is shaped similarly to the cap 60 plate. The cap plate and the back plate have portions 11, that are shaped to conform 65 to the heel portion of the shackle 5, Fig. 1, and extend on each side of the shackle, as shown. The shackle 5 enters an opening 12 70 in the casing and is engaged by the ordinary locking mechanism, not shown. Extending from the casing between the two portions of the shackle is a rib 13, which is shaped as shown in Figs. 2 and 3, so as to fit 75 a portion of the groove 2 in the pin 1 when the shackle is in the closed position. The shackle is shaped to fit the other portion of the groove, as clearly shown in Figs. 2 and 3, so that, when the shackle is in the locked 80 position, the lock casing is held onto the pin, preventing the withdrawal of the spare wheel from the pin, but the lock casing can turn freely on the pin so that it is difficult to hold the lock in the endeavor to free the shackle without a key. Two or more 85 grooves are preferably formed in the pin to accommodate wheels having different thicknesses of hub, although, where a pin is made for a special type of wheel, one 90 groove is sufficient.

In Figs. 6 and 7, a modification is shown in which one side of the pin 1^a is flat to fit the flat surface 13^a of the casing 4^a of the lock. In this modification, the lock cannot 95 turn on the pin.

In Figs. 8 and 9, the pin 1^b is shown with a main groove 2^a for the shackle 5^b, and a groove 2^b on each side of the main groove for the ribs 13^b on the cap plate and back 95 plate of the lock 4^b.

Fig. 10 illustrates a modification, in which only one of the plates of the lock 4^c has a rib 13^c adapted to a groove 2^c at the side of the main groove. This lock can only be 100 placed in position with the face outwards so that, when the key hole is in the face, it is always accessible.

Fig. 11 is a view showing the invention applied to a lock having a sliding shackle 5^d. 105 The rib 13^d projects into the groove of the pin 1^d between the arms of the shackle.

Fig. 12 shows a pin 1^e having a head and a

reduced portion 2° back of the head to receive the shackle and the rib in the lock casing.

Fig. 13 is a view showing the invention applied to a hinged door. The pin 1° is flanged and is threaded to receive a nut 15, which secures the pin to the door jamb 14. The door 16 has an opening 17 through which the grooved portion of the pin extends. The lock 4 is secured to the projecting portion of the pin, holding the door closed.

In Figs. 14 and 15, a two-part pin is illustrated, which is particularly adapted to secure sliding doors in position. The two parts 1° are each secured to a sliding door 18. When the doors are closed, as in Figs. 14 and 15, the two parts form a complete pin with an annular groove therein to receive the padlock.

In Fig. 16, a pin is shown made of struck up sheet metal. It will be understood that the groove, or reduced portion of the pin, may be of any shape desired to correspond with the shape of the shackle and the rib on the lock casing.

We claim:

1. The combination in a padlock, of a casing having a body portion, a cap plate and back plate; and a shackle adapted to the casing, said casing having a rib projecting into the space between the arms of the shackle, the

cap plate and back plate having portions extending on each side of the shackle at one side of the casing and conforming to the shape of the shackle.

2. The combination in a lock, of a body portion; a shackle pivoted thereto, said body portion having a back plate and a cap plate, each of said plates having an extension at the pivot end of the shackle and conforming to the shape of the shackle, the lock casing having a rib extending into the space between the arms of the shackle, the rib and the shackle being arranged to enter a groove in a projecting pin.

3. The combination of a two part pin, each part having a groove therein, the grooves being in alignment one with the other; a lock casing having a rib, and a shackle on the lock casing, the shackle and rib arranged to enter the groove in the two part pin.

4. The combination in a padlock of a casing consisting of a body portion and cap and back plates, a shackle the same width as the body portion; the body portion having a rib of the same width as the shackle and extending beyond the front and back plates and between the arms of the shackle and arranged to engage a pin projecting through the space between the shackle and rib.

ARTHUR C. JACKSON.
WALDEMAR KROLL.
